US00D755843S

(12) **United States Design Patent**
Akana et al.

(10) **Patent No.:** US D755,843 S
(45) **Date of Patent:** ** May 10, 2016

(54) **DISPLAY SCREEN OR PORTION THEREOF
WITH GRAPHICAL USER INTERFACE**

(71) Applicant: **Apple Inc.**, Cupertino, CA (US)

(72) Inventors: **Jody Akana**, San Francisco, CA (US);
Jonathan P. Ive, San Francisco, CA (US);
Britt Nelson, San Francisco, CA (US);
Wan Si Wan, Sunnyvale, CA (US);
Christopher Wilson, San Francisco, CA (US)

(73) Assignee: **Apple Inc.**, Cupertino, CA (US)

(**) Term: **14 Years**

(21) Appl. No.: **29/457,357**

(22) Filed: **Jun. 10, 2013**

(51) LOC (10) Cl. **14-04**

(52) U.S. Cl.

USPC **D14/492**

(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface showing our new design;

FIG. 2 is another embodiment thereof; and,

FIG. 3 is another embodiment thereof.

The broken lines in the figures show a display screen or portion thereof, and form no part of the claimed design.
